Des. 187,512
Patented Mar. 22, 1960

187,512

FORCED DRAFT BURNER

Ralph R. Vosper, Cupertino, Calif., assignor to Coen Company, San Francisco, Calif., a corporation of California

Application April 10, 1957, Serial No. 45,669

Term of patent 14 years

(Cl. D81—1)

Fig. 1 is a front elevational view of a forced draft burner showing my new design;

Fig. 2 is a side elevational view thereof;

Fig. 3 is a top plan view thereof.

Fig. 4 is a rear elevational view thereof; and

Fig. 5 is an elevational view of the side of the burner opposite that shown in Fig. 2.

I claim:

The ornamental design for a forced draft burner, as shown.
